CLOTHES RACK

Paul D. Parks, Winona Lake, Ind.

Application May 3, 1949, Serial No. 2,416

Term of patent 14 years

(Cl. D33—8)

To all whom it may concern:

Be it known that I, Paul D. Parks, a citizen of the United States, residing at Winona Lake, in the county of Kosciusko and State of Indiana, have invented a new, original, and ornamental Design for a Clothes Rack, of which the following is a specification, reference being made to the accompanying drawing, forming a part hereof.

In the drawing:

Fig. 1 is a side view in perspective and showing a clothes rack embodying my new design; and

Fig. 2 is a plan view thereof.

I claim:

The ornamental design for a clothes rack, substantially as shown.

PAUL D. PARKS.
